WELL DRILLING ASSEMBLY

Wilfred S. Crake, Houston, Tex., assignor to Shell Oil Company, New York, N.Y., a corporation of Delaware
Filed Sept. 11, 1961, Ser. No. 137,147
5 8 Claims. (Cl. 175—325)

This invention relates to the drilling of wells in earth formations such as oil and gas wells, and pertains more particularly to a well drilling apparatus employing a unique drill collar designed to reduce the tendency of a drill bit to wander from a vertical line, especially when drilling through steeply dipping formations.

In drilling oil wells, one or more heavy drill collars are generally interposed between the drill bit and the rest of the drill string in order to concentrate a predetermined heavy weight on the bit so as to produce the best rate of drilling. Drill collars generally take the form of thick-walled pipe sections which may be 20 or more feet in length and are provided with a central bore therethrough for circulating a drilling fluid to the bit. The drill collars, together with the rest of the drill string secured to the top of the uppermost collar, forms an elongated steel column which pushes the drill bit downwardly against the formation. Because of the length and flexibility of this elongated steel column of drill pipe and collars, the steel column bends slightly so as to contact the wall of the well bore at several points between the bottom of the well and the surface of the ground. The spacing between adjacent points of contact between the flexible drill string and the borehole wall increases as the points of contact get higher in the borehole due to the fact that there is less weight of drill pipe being exerted downwardly at the higher points of contact.

Thus, the lowermost part of the drill string or drill collar between the bit and the first point at which the drill collar contacts the wall of the borehole, will form an angle to the true axis of the borehole. If the lowermost portion of the borehole should happen to be vertical, which is seldom the case, the axis of the lowermost portion of the drill collar would lie at a small angle to the vertical since the wall of the drill collar would lay against the wall of the borehole at some point above the bit. In the more normal case, where the axis of the well bore was, say, 2° to the vertical, the drill collar would lay against the lower side of the borehole and its axis may form an angle of, say, 3° to the vertical. In either case there is a tendency for the drill bit to drill off at an angle to the axis of the borehole thus causing a deviation which results in a crooked hole. When drilling operations are carried out with the drill collar touching the wall by bending a small amount, the axis of rotation of the drill collar remains in the center of the collar as it rotates around its bent axis, thus pointing the bit at a slight angle to the true bore of the well. As drilling operations are continued in the well, this angle causes the amount of horizontal deflection of the well from the vertical to increase. It is presently known that the deflection of the drill string and bit can be decreased by reducing the weight on the drill column or by utilizing at least one full-hole-diameter stabilizer at a suitable height above the bit so that the portion of drill collar below the stabilizer acts as a pendulum which tends to exert a force causing the bit to come back toward the vertical again. However, with all the known aids and techniques of drilling presently available, crooked well bores are still being drilled practically all of the time.

It is therefore a primary object of the present invention to provide a well drilling assembly adapted to counteract any tendency of a drill bit to drill off at an angle from the desired vertical borehole.

2

It is known that, when drilling through formations which are inclined or dip at an angle to the horizontal, a rotating drill bit tends to drill up-dip, or tries to drill in a direction normal to the formation dip planes. The angle at which formations dip is one of the major forces tending to produce a deflection of a drill bit which is normally inclined to the two axis of a borehole at a slight angle as described hereinabove. The direction of inclination of a borehole is predominantly fixed toward a plane normal to the formation dip, and thus the direction in which the axis of the drill collar is pointed is also controlled and fixed. Thus, continued drilling through a dipping formation results in a borehole with increasing deflection until a point is reached where it is necessary to employ various types of tools well known to the art to head the bit back in a vertical direction again.

It is therefore another object of the present invention to provide a well drilling apparatus adapted to constantly correct any deviation of the borehole from the vertical so as to eliminate the need for installing special equipment in the borehole to bring a crooked hole back to normal.

A further object of the present invention is to provide a well drilling assembly in which any tendency to deflect from the vertical when drilling through sloping or dipping formations is greatly reduced or substantially eliminated.

These and other objects of this invention will be understood from the following description taken with reference to the drawing, wherein:

FIGURE 1 is a longitudinal diagrammatic view illustrating the lower end of a drill string with drill collars positioned in a well;

FIGURES 2 and 3 are diagrammatic views illustrating two arrangements of the drilling assembly of the present invention when positioned in a well;

FIGURES 4, 5 and 6 are horizontal views of various modifications of the drill collar of the present invention; and,

FIGURES 7, 8 and 9 are cross-sectional views of FIGURES 4, 5 and 6, respectively, taken along the line A—A.

Referring to FIGURE 1 of the drawing, a drill string is illustrated as being made up of a plurality of sections of drill pipe 11, 12, 13 and 14 and a pair of drill collars 15 and 16 with a bit 17 secured to the lower end of the lowermost drill collar 16. If desired the drill collars may be provided, at one or more levels, with a series of radially-extending rib elements or any other suitable type of centralizer or stabilizer device which is fastened to the outside of the drill collars so as to reduce the amount of play between the outer surface of the drill collars and the wall of the borehole 20. In the design of the centralizer or stabilizer device illustrated in FIGURE 1, a series of radially-extending ribs 21 are welded to the outer surface of the drill collar 15, preferably in a diagonal direction. When weight is applied to the lower end of the drill string during drilling operations, the drill string would lay against the wall of the borehole at several points. Since the stabilizer ribs 21 project outwardly from the collar, they would probably form one point of contact for the drill string with the borehole wall, so that the section of the drill string below the stabilizer 21 would assume an angle to the vertical axis of the borehole. Continued drilling of the hole would cause the borehole to deviate from the vertical at an angle assumed by the drill collars.

In FIGURE 2 the drill collar 22 of the drilling assembly of the present invention is designed to have its axis temporarily locked at an angle under load conditions by providing a section modulus of the collar 22 which is predominantly greater in one direction than in another. Any suitable means may be employed for reducing the section modulus of a portion of the drill collar so that the collar is preferentially bendable in one direction. For example,

s illustrated in FIGURES 2 through 9, the section-modulus-reducing means takes the form of a portion of the collar having a reduced wall thickness which is formed in a manner so that the wall is thicker on one side than the other. For example, in FIGURE 2 the wall thickness of drill collar 22 is reduced by cutting a slot 23 into the wall of the collar from the outside thereof, preferably on a line normal to the axis of the collar. When column loading is applied to the top of drill collar 22, the collar 2 will be caused to bend at the slot 23 since the section modulus of the collar is predominantly greater in one direction than in a direction taken at 180° to the slot. As long as a load is applied to the top of the drill collar 22, its axis will remain locked at a slight angle from the vertical, as illustrated in FIGURES 2 and 3, although it is to be understood that the illustrated angle in these figures is greatly exaggerated.

Since the side of the drill collar 22 diametrically opposite the slot 23 will bear against the borehole wall 24, suitable bearing means or wear reducing means 25 are provided. For example, one form of bearing means or wear reducing means may take the form of a hard-surfaced area of some suitable material such as tungsten carbide which would reduce the wear of that portion of the outer wall of the collar 22 in contact with the wall of the borehole. Alternatively, one or more rollers rotating on a substantially vertical axis could be positioned on the outer wall of the collar 22 opposite the slot 23.

The slot 23 of collar 22 is shown in greater detail in FIGURES 4 and 7. The exact position of the slot 23 along the collar 22 and the size and depth of the slot 23 would vary depending upon the load conditions, the diameter of the collar, the thickness of the wall of the collar, the material of which the collar is made, etc. For a bit drilling an 8 1/4 inch hole, a 7 1/2 inch drill collar having 3/4 inch bore may be employed. Instead of using a single slot 23, a second slot 26 in the opposite wall may be cut to allow bending of the collar 22 under a lighter load. As an example, the slot 23 of the 7 1/2 inch drill collar may be 3/4 inches deep while the slot 26 positioned diametrically opposite may be one inch deep. For this particular size drill collar the slots 23 and 26 are preferably positioned above the bit a distance less than 20 times the diameter of the hole being drilled. The distance between the bit 17 and the slots 23 and 26 determines the angle of the drill collar 22 to the normal borehole wall when the axis of the drill collar is locked so that the portion of the outer wall adjacent the smaller slot 26 contacts the wall of the borehole. Thus, an angle of 0 degree 19 minutes is formed between the axis of the drill collar and the axis of the hole when the slotted portion of the collar contacts the wall at a height 10 feet above the bit. When the height is 8 feet, the angle is 0 degree, 23 minutes.

It is to be understood that instead of cutting the slot 23 in the outer wall of the drill collar, a flat or other suitable configuration may be milled in the wall of the collar so as to preferentially reduce the wall thickness on one side thereof so that the collar will bend at the point of section modulus. In the event that the collar 28 (FIGURE 6) has an extremely thick wall, a portion 29 of the collar may be reduced in diameter with a slot 30 cut in one wall to further reduce the section modulus.

When the drill collar 22 of FIGURE 2 is column-loaded from above so that its axis is locked at a predetermined angle from the axis of the borehole, upon rotation of the drill string the axis of the collar 22 below the slot 23 describes a conical surface around the bit center of rotation and thus causes the bit to directionally drill at the same angle to all points on the compass as it rotates. With the bit directionally-drilling to all points of the compass, deflection of the bit which would normally take place is substantially reduced and in some formations eliminated. To aid further in reducing any deflection, the well drilling assembly may be provided with one or more centralizers or stabilizers of any suitable design which are

diagrammatically illustrated in FIGURE 2 as element 32. The stabilizer or centralizer 32 is positioned above the bit, preferably at a distance equal to twice the distance between the bit and the slot 23.

In order to provide a more positive and controlled bent axis to the drill collar 22 (FIGURE 2), the drill collar or collars positioned above the collar 22 may be of the fully-packed-hole type of drill collar which has a diameter substantially equal to that of the bit, or having a diameter that is only 1/8 or 1/4 of an inch smaller than the diameter of the borehole. One form of a drill collar of this type is illustrated as collar 15 in FIGURE 1 which is provided with spiral elements or blades 21 which would reduce the vibration in the upper collars which is caused by the bent axis of the lowermost collar. Instead of a round drill collar being used, the upper collar or collars 15 may be square in cross section with the diagonal dimension being slightly less than the borehole diameter. By such means, adequate annular clearance for cuttings removal is provided and still a "packed hole" is maintained.

Another form of the well drilling assembly of the present invention is illustrated in FIGURE 3 as comprising a drill collar 33 having three pairs of slots 34 and 35, 36 and 37 and 38 and 39 which are cut in the outer wall thereof in a manner illustrated by the slots 23 and 26 of FIGURE 5. A preferential bend direction is imparted to the collar 33 by making the deeper cuts 34, 36 and 38 on the side of the collar toward which it is desired to have the collar bend. By making two consecutive cuts 34 and 36 deeper on one side a sort of crank angle is formed with a flat portion of the collar between cuts 35 and 37 contacting the borehole wall to act as an elongated bearing surface thereagainst which is provided with suitable hard surfacing. The greater the weight on the column of drill string and the collars attached thereto, the greater will the thrust on the section in contact with the borehole between slots 35 and 37, but due to the length chosen between the cuts or slot, all of the sections of drill collar on each side of the slots are so stiff that insignificant bending takes place in them. In this case the distance between the bit and slot 34 is 8 feet, between slots 34 and 36 there is a 6 foot interval with 8 foot intervals between slots 36 and 39 and between slot 39 and the stabilizer or centralizer 32. In this case, with an 11 inch outside diameter drill collar 33 positioned in a 12 1/4 inch borehole 40 the section of the collar between the bit 17 and the first slot 34 assumes an angle of about 0 degree 24 minutes with the axis of the borehole 40. The horizontal thrusts at the slots and the bit, with 100,000 lbs. column load on the drill string, are 700 lbs. at each point, and the bearing load on the surface 41 parallel to the borehole wall is 1,400 lbs. from the thrust.

I claim as my invention:

1. Apparatus to minimize well deviation during drilling a well comprising a drill string adapted to be positioned in a well, at least one thick-wall drill collar secured to the lower end of said drill string, and a drill bit secured to the lower end of said drill collar and rotatable with said collar and said drill string, a portion of said drill collar being formed with reduced wall thickness only on one side thereof to reduce the section modulus of the collar directionally, whereby under load conditions the axis of the drill collar below the portion of reduced section modulus becomes locked in one direction at an angle to the axis of the well whereby the angle formed in the collar sweeps around the wall of the well.
2. The apparatus of claim 1 wherein the portion of the reduced wall thickness comprises a horizontal slot cut partially into the wall of said collar from the outside and less than the wall thickness thereof.
3. The apparatus of claim 1 including bearing means carried on the outer wall of said drill collar adjacent the reduced wall thickness portion thereof.
4. The apparatus of claim 3 wherein the bearing means

comprises hard-surfacing material affixed to the outer surface of said drill collar.

5. The apparatus of claim 1 including stabilizer means secured to said drill string adjacent the top of said collar.

6. The apparatus of claim 1 wherein said drill collar has a horizontal dimension substantially equal to the diameter of the well being drilled by the bit.

7. Apparatus to minimize well deviation during drilling a well comprising a drill string adapted to be positioned in a well, at least one thick-wall drill collar secured to the lower end of said drill string, and a drill bit secured to the lower end of said drill collar and rotatable with said collar and said drill string, a portion of said drill collar being formed with reduced wall thickness to reduce the section modulus of the collar directionally, the portion of reduced wall thickness being a pair of horizontal slots cut partially into the wall of said collar from the outside thereof, said slots being at points substantially diametrically opposite each other, one of said slots being deeper than the other, whereby under load conditions the axis of the drill collar below the portion of reduced section modulus becomes locked in one direction at an angle to the axis of the well whereby

the angle formed in the collar sweeps around the wall of the well.

8. Apparatus to minimize well deviation during drilling a well comprising a drill string adapted to be positioned in a well, at least one thick-wall drill collar secured to the lower end of said drill string, and a drill bit secured to the lower end of said drill collar and rotatable with said collar and drill string, there being three axially-spaced portions of said drill collar being formed with reduced wall thicknesses to reduce the section modulus of said collar directionally, whereby under substantially vertical loading conditions the axis of the collar is bent and locked at an angle to the drill string, two portions of the collar with reduced wall thickness nearest the bit being on the same side of the collar with the third portion being on the opposite side of the collar.
